PRESSURE DRUM MANHOLE COVER AND
INTERNAL SUPPORT THEREFOR

Floyd H. Skinner, Parkchester, N. Y., assignor to
Combustion Engineering, Inc., New York, N. Y.,
a corporation of Delaware

Application April 8, 1952, Serial No. 281,111

3 Claims. (CL 220—34)

1

This invention relates to improved supports for manhole covers inside of pressure vessels and particularly to manhole covers for the steam and water separating drums of steam generators.

In a steam generator drum containing steam separating or washing apparatus, the drum space is generally divided into compartments, one of which receives steam and water mixture from the steam generating tubes of said generator. From this one compartment the mixture flows into and through apparatus in which the steam and water are separated or wherein the steam is washed, whence the steam flows into another compartment comprising the remaining portion of the drum. This other or second compartment is at a pressure below that of the first mentioned compartment and therefore must be sealed therefrom by suitable means including end sealing partitions. Said sealing partitions extend transversely of the drum beyond the end tubes that deliver said steam and water mixture into said compartment and it is extremely desirable to limit the distance from said end sealing partitions to the drum heads to a practical minimum in order to reduce the overall drum length. It is within this limited distance that the manhole cover must swing to and from the open and closed position.

It is an object of this invention to provide improved means for supporting inside manhole covers for pressure vessels while the covers are being moved away from the closed to the extreme open position into the vessel, said means requiring a practical minimum distance within said vessel for said movement.

Additional objects and advantages will become apparent from the following description of illustrative embodiments of the invention when read in conjunction with the accompanying drawings wherein:

Figure 1 is an exterior view of a typically horizontally disposed steam and water drum taken from the side thereof.

Figure 2 is a horizontal longitudinal sectional view taken along line 2—2 of Fig. 1 with the manhole cover and improved means for supporting the same shown in elevation.

Figure 3 is an elevation taken on line 3—3 of Fig. 2 showing the manhole cover in the closed position together with the improved cover supporting means.

Figures 4 and 5 are similar to Figs. 2 and 3 and show a modification of the invention.

In the drawings, wherein like symbols represent like parts, pressure vessel 1 is shown as

2

having an outwardly dished head 2 with an inwardly extending flanged portion 3 forming a manhole 4. An inside cover 5 contacts seat 6 of said flanged portion 3 and forms a closure for said manhole. Bolts 7 extend outwardly from said cover through suitable holes in arches 8. The heads 9 of said bolts 7 removably fit into sockets 10 provided in the cover 5. Nuts 11, threadedly received on the outer end of said bolts, bear against the outer surface of arches 8, which in turn bear against the outer surface of head 2 as shown in Figs. 1, 2 and 4. By drawing up on the nuts 11 cover 5 is held in firm-engagement with seat 6.

When the bolts 7 and arches 8 are removed, the cover 5 is supported by means of a suitable link 12 rotatably secured to said cover and to vessel head 2. In the organization shown in Figs. 2 and 3 link 12 is mounted to rotate around the center *a* provided in bracket 13 secured to the vessel head 2 as by welding. Said bracket 13 is generally U-shaped and has its flanges 14 bored to receive leg 15 of link 12, with leg 16 of said link being rotatably received by a similar bracket 17 secured to cover 5. Said bracket 17 is also generally U-shaped and has its flanges 18 bored to receive said leg 16 whereby rotation about axis *a'* is provided. Collar 19, provided on leg 15 of link 12, supports said link against downward movement and a nut 20 and washer 20' on leg 16 of said link 12 supports bracket 17 and therewith cover 5.

When said cover 5 is swung away from the manhole 4 about pivot *a* to its extreme position 35 within vessel 1 (as indicated by the dot-dash line 21 in Fig. 2) it is then so positioned as to occupy the least possible distance longitudinally of the drum while being entirely free of said manhole 4. Such location of the cover 5 in steam and water drum 1 not only provides free access to the interior of said drum but in addition provides that any transverse partition, such as partition 22, may be positioned more closely to head 2 thereby reducing the overall length of drum required with obvious savings in material and handling.

Partition 22 may be the end plate of apparatus such as a steam separator or steam washer through which passes all of the steam and water mixture being discharged into drum 1 via steam generating tubes 23. Said partition 22 must be located outwardly of the endmost of said tubes 23 in order to direct said steam and water mixture through said steam separator or washer wherefore it is apparent that the overall length of drum 55 depends not only on the number of longitudi-

nally arranged steam generating tubes 23 but also on the distance between partition 22 and drum head 2 required to move cover 5 from the closed to the extreme open position. This distance becomes a practical minimum when cover 5, in its extreme open position, is in the location shown by the dot-dash line 21.

I have found that said cover 5 may best be swung into said open position with the least possible longitudinal distance of said vessel being 10 required when the pivotal center a' of bracket 17 is offset from the center f' of said cover in a direction generally toward bracket 13 as viewed in the cover closed (the solid line) position of Fig. 2. If the center a' were located centrally of cover 5 (at f'), as has been customary heretofore, said cover 5 would be further from the drum head 2 when in the open position, by a distance equal to $a'f'$. Drum head 2 would then have to be moved 15 away from the partition 22 to provide the additional clearance for said cover 5 and consequently the overall drum length would have to be increased.

The amount of offset from the center of the cover is not limited to the distance $a'f'$ or $a''f''$, but may be greater or even somewhat less. In Fig. 2 are shown arbitrarily chosen offsets $b'f'$, $c'f'$ and $d'f'$ corresponding to $b''f''$, $c''f''$ and $d''f''$ respectively, in the position indicated by dot-dash line 21. Each of these offsets permits 20 the cover 5 to rotate about pivots b , c and d respectively, from closed to extreme open positions within the same limited distance between partition 22 and drum head 2. The extreme open position of cover 5 will, in each case, be substantially the same as that shown by the dot-dash line 21. The radii bb' , cc' and dd' or correspondingly bb'' , cc'' and dd'' of the respective links, will be substantially the same as the radius aa' or aa'' of link 12. It is to be understood that the locations of the pivots a , b , c and d , with respect to their distance from the drum is not limited to those shown so long as their centers fall on lines bisecting the angles $a'aa''$, $b'bb''$, $c'cc''$ and $d'dd''$ respectively. The distance that said pivots can be moved inwardly is, however, limited by the necessity of avoiding interference with the front face of cover 5 when said cover occupies its extreme open position.

The distance that pivotal centers a , a' are spaced apart, i. e., the effective length of link 12, can conveniently be made to substantially equal the distance between pivotal center a' and the farthest edge 26 of cover 5; since with said link being of such length and with said center a displaced outwardly of seat 6 said edge 26 will easily clear said seat when the cover is moved to the extreme open position.

The modification shown in Figs. 4 and 5 is similar to that just described with the exception that the connection of the link with the manhole cover is through the medium of an additional connector link rather than directly to said cover.

Referring specifically to said Figs. 4 and 5 it will be noted that link 29, by way of example only, is shown as connecting pivotal centers b , b' in lieu of a , a' as in the case of the embodiment of Figs. 2 and 3. Said link 29 has one end rotatably mounted about a pivotal center b in bracket member 13' and the other end received within suitable openings provided in connector link 28 for rotation about a pivotal center b' , which pivotal center is offset from the center of cover 5 as shown.

Said connector link 28 is pivoted to bracket 17

75 through the medium of pin 27 disposed in aligned openings in said connector link and said bracket. Said bracket 17, in this embodiment, is located centrally of the cover wherefore the pivotal center located within said bracket, herein designated f' , also has a central location.

The provision of pivotally mounted connector link 28 permits adjustment of cover member 5 with respect to seat 6 as well as providing the desired offset for pivotal center b' . Thus, in this embodiment, the cover is universally adjustable since connector link 28 provides adjustment lengthwise of link 12 while the mounting of the leg of said link in the openings in said connector link 28 provides adjustment laterally of said link 12.

It will thus be seen that I have provided a novel support for the manhole cover of a steam and water drum which permits said cover to be swung to and from an extreme open position where it is entirely free of the manhole opening while requiring the least possible distance longitudinally of the drum.

While illustrative embodiments of my invention have been here shown and described, it will be understood that changes in construction, combination and arrangement of the parts may be made without departing from the spirit and scope of the invention as claimed.

I claim:

1. In a pressure drum having a generally rounded end portion with a manhole opening centrally thereof formed by means of an inwardly projecting flange providing a seat means at its inner extremity, a manhole cover for said opening arranged to seat on said seat means and a partition extending transversely of said drum at a predetermined distance from said end; the improvement comprising means for supporting said cover within said vessel in a manner to permit movement thereof from a closed position in engagement with said seat to an open position entirely free of interference with access to the interior of said drum through said opening, said means including a generally U-shaped link having one leg thereof pivotally mounted within said drum about a pivotal axis located outwardly of said seat and adjacent to said rounded end, the other end of said link being effectively pivoted to said cover about an axis laterally offset a predetermined distance from the center of said cover in a direction toward the axis of rotation of said one leg when said cover occupies its closed position in engagement with said seat, the effective length of said link being substantially equal to the distance from said effective pivotal axis to the most remote edge of said cover with the legs of said link being of sufficient length to permit rotation of said cover through the space enclosed by said legs, whereby said link may be rotated about its pivotal connection to the drum to move said cover from the closed to the extreme open position simultaneously with which said cover may be rotated in the opposite direction about said effective pivotal axis to a point where the edge of said cover that is most remote from said effective pivotal axis lies in juxtaposition to but spaced from said seat thereby requiring a practical minimum predetermined distance between said transverse partition and said drum end for the opening and closing movement of said cover.

2. In a pressure drum having a generally rounded end portion with a manhole opening centrally thereof formed by means of an inward-

ly projecting flange providing a seat means at its inner extremity, a manhole cover for said opening arranged to seat on said seat means and a partition extending transversely of said drum at a predetermined distance from said end; the improvement comprising means for supporting said cover within said vessel in a manner to permit movement thereof from a closed position in engagement with said seat to an open position entirely free of interference with access to the interior of said drum through said opening, said means including a generally U-shaped link having one leg thereof pivotally mounted within said drum about a vertical axis located outwardly of said seat and adjacent said rounded end, a support bracket secured to the inner face of said cover a predetermined distance laterally of the center thereof in a direction toward the axis of rotation of said one leg when said cover occupies the closed position in engagement with said seat, the other leg of said link being rotatably received within suitable openings in said support bracket in a manner to provide a similarly laterally displaced pivotal axis for said cover, the effective length of said link being substantially equal to the distance from said pivotal axis for said cover to the most remote edge of said cover and the legs of said link being of sufficient length to permit rotation of said cover through the space enclosed by said legs, whereby said link may be rotated about its pivotal connection to the drum to move said cover from the closed to the extreme open position simultaneously with which said cover may be rotated in the opposite direction about its pivotal axis toward a point where the edge of said cover that is most remote from the cover's pivotal axis lies in juxtaposition to but spaced from said seat, thereby requiring a practical minimum predetermined distance between said transverse portion and said end for the opening and closing movement of said cover.

3. In a pressure drum having a generally rounded end portion with a manhole opening centrally thereof formed by means of an inwardly projecting flange providing a seat means at its inner extremity, a manhole cover for said opening arranged to seat on said seat means and a partition extending transversely of said drum at a predetermined distance from said end; the improvement comprising means for supporting

5 said cover within said vessel in a manner to permit movement thereof from a closed position in engagement with said seat to an open position entirely free of interference with access to the interior of said drum through said opening, said means including a generally U-shaped support link having one leg thereof pivotally mounted within said drum about a pivotal axis located outwardly of said seat and adjacent said rounded end, a bracket secured centrally of said cover, a connector link pivoted to said bracket about a centrally disposed axis generally parallel to the axis of rotation of said one leg, the other end of said support link being pivotally secured to the distal end of said connector link with the pivotal axis being located a predetermined distance laterally of the center of the cover in a direction toward the axis of rotation of said one leg when said cover occupies the closed position in engagement with said seat, the effective length of said support link being substantially equal to the distance from said pivotal axis of said other leg to the most remote edge of said cover and the legs of said support link being of sufficient length to permit rotation of said cover through the space enclosed by said legs, whereby said support link may be rotated about its pivotal connection to the drum to move said cover from the closed to the extreme open position simultaneously with which said cover may be rotated in the opposite direction about the pivotal axis for said other leg to a point where the aforementioned remote edge of said cover lies in juxtaposition to but spaced from said seat, thereby requiring a practical minimum predetermined distance between said transverse partition and said head for the opening and closing movement of said cover.
